CARL THEODOR THORSSSELL, EBBE CHRISTIAN BECK-FRIIS, AND ERNST ERIK DAVID EDLUNDH, OF GOTTFENBORG, SWEDEN.

CHARGING HOPPER FOR ELECTRIC FURNACES.

Application filed June 20, 1921. Serial No. 479,071.

Our invention comprises improvements in charging devices for electric furnaces, and the object of the invention is to eliminate the disadvantages incident to the collecting of the escaping gases.

In a furnace with uniform gas generation if the mass to be treated is carried downwards, while the escaping gases pass in the opposite direction and preheat the material, 10 the velocity of the latter will be reduced on account of the frictional resistance against the walls causing the mass here to be heated to a higher temperature in such a way that the temperature in a horizontal layer becomes different at the middle and at the 15 sides. If the material is particularly sensitive to such an irregularity of the temperature this disadvantage may be disastrous. Besides, the material must be stirred repeatedly along the furnace walls and in 20 front of the electrodes placed in the walls, and when the temperature is measured by means of measuring rods, holes must be provided for these rods. At such stirring 25 and measuring of the temperature the shutters must be opened and thus the gas escapes. On the other hand, if receptacles for the material are to be arranged above the furnace in order to save working power it is difficult 30 to provide such without colliding with the shutters and holes mentioned.

These inconveniences are remedied by the present invention which is characterized by a device allowing the material to pass downwards along the sides of the furnace while the gas is taken out at the centre. Stirring holes and the like may be arranged in such a way that they may be opened without any considerable loss of gas. Further the 40 preheating of the material passing through the furnace is most efficient at the centre of the furnace while the material at the side walls of the furnace, which material is not so much or not at all preheated by the escaping gases, endures a stronger heating and thus the temperature is equalized in such a way that it becomes uniform through the whole inner cross-section of the furnace.

By arranging valves controllable from the 50 outside in the lower part of the gas outlet the gas current can be controlled and also the heat conditions in the furnace in some measure regulated in such a way that, if for instance the temperature in a certain part of 55 the furnace is found to be too high, the hot

gases may be directed through other parts of the material. By dividing the gas chamber in sections each provided with a separate outlet and a separate controlling valve the same result can be attained.

60

One form of the invention is shown in the accompanying drawings, in which:

Fig. 1 is a section on line 1—1 of Fig. 3.
Fig. 2 is a section on line 2—2 of Fig. 3.
Fig. 3 is a section on line 3—3 of Fig. 1. 65
Fig. 4 is a plan view of the apparatus.

On the shell plate 2 extending above the upper rectangular part 1 of the furnace two charging hoppers 3 or the like are provided for the material to be treated in the furnace. Under these charging hoppers a distributing plate 4 for the material is arranged, said plate being roof-shaped and having its lower edge at a suitable distance from the shell plate 2. The distributing 75 plate 4 is extended downwards with four vertical sides 5 between which and the furnace walls the material passes down into the furnace from the charging hoppers 3. Thus the material introduced into the furnace passes only along the side walls of the furnace, and the upper surface of the material will form a ditch-shaped cave 6 in the center of the furnace under the distributing plates 4 and 5. The gas outlet is arranged inside 80 of the distributing roof and consists of a hood 7 extending from the lower edges of the distributing plates 5 and converging upwards where it is connected with an outlet pipe 8. Stirring holes 9' and holes 9'' for 85 measuring the temperature are provided. By means of short vertical plates as 10 arranged across the charging passages each stirring hole is separated from the neighbouring hole in such a manner that the leaking of gas at the stirring operation will be essentially reduced and eventual gas explosions localized that is in the sections 10'. The distributing plate and the hood of the 90 gas outlet may also be combined in such a way that a common sheet for them both is used, as indicated at 11.

By this arrangement the gases generated in the furnace will be directed towards the centre of the furnace, i. e. towards the cave 105 6 under the hood 7 from where they escape through the outlet 8. The material passing downwards into the furnace along the furnace walls will not be subjected to any intense preheating as the gases pass upwards 110

5 towards the central parts of the furnace and here get an opportunity of preheating that portion of the material which is mostly in need of a preheating, i. e. the material 10 passing more rapidly through the furnace. The result is a uniform heating of all the material in the furnace.

10 It is evident that the gases in a known way can be directed to different parts of the material passing through the furnace, for instance by placing a number of valves 12 at the lower edge of the gas outlet 7 controllable from the outside as at 12'. If for instance the temperature in a certain place becomes too high 15 certain valves are closed so that the gas is directed to other valves through other parts of the mass in the furnace.

What we claim is:—

1. A charging hopper for electric furnaces, comprising a distributing member arranged at the upper end of the furnace and diverging downwardly, a gas outlet arranged beneath said distributing member and converging upwardly, and an outlet pipe connected with the upper part of said gas outlet, and means associated with said gas outlet for directing the gases to different parts of the material in the furnace.

2. A charging hopper for electric furnaces, comprising a distributing member arranged at the upper end of the furnace and diverging downwardly, a gas outlet arranged

35 beneath said distributing member and converging upwardly, an outlet pipe connected with the upper part of said gas outlet, and a valve arranged in the gas outlet for directing the gases to different parts of the material in the furnace.

3. A charging hopper for electric furnaces, comprising a distributing member arranged at the upper end of the furnace and diverging downwardly, the lower edges of the distributing member being spaced from the walls of the furnace, a gas outlet arranged beneath said distributing member and converging upwardly, and an outlet pipe connected with the upper part of said gas outlet, and means associated with said gas outlet for directing the gases to different parts of the material in the furnace.

40 4. A charging hopper for electric furnaces, comprising a distributing member arranged at the upper end of the furnace and diverging downwardly, a gas outlet arranged beneath said distributing member and converging upwardly, said gas outlet being formed in sections, each having a valve controlled outlet, and an outlet pipe connected with the upper part of said gas outlet.

45 In testimony whereof, we have signed our names to this specification.

CARL THEODOR THORSELL.
EBBE CHRISTIAN BECK-FRIIS.
ERNST ERIK DAVID EDLUNDH.
